UNITED STATES PATENT OFFICE.

MORRIS ROSENWASSER, OF NEW YORK, N. Y.

LEGGING.

No. 857,963.

Specification of Letters Patent.

Patented June 25, 1907.

Application filed January 8, 1907. Serial No. 351,304.

To all whom it may concern:

Be it known that I, MORRIS ROSENWASSER, residing at New York, in the county of New York and State of New York, have invented 5 certain new and useful Improvements in Leggings, of which the following is a full, clear, and exact description, such as will enable others skilled in the art to which it appertains to make and use the same.

10 This invention relates to garments and more particularly to leggings.

One of the objects of the invention is to provide a legging which will fit about the leg with greater accuracy and which will better

15 retain its shape when upon the leg than will leggings as hitherto constructed.

Another object is to provide a simpler and more efficient manner of fastening the legging upon the leg than has hitherto been devised.

20 Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

25 In the accompanying drawing, wherein is illustrated one of the various possible embodiments of my invention, Figure 1 is a view showing the interior of the legging, which has been flattened out better to illustrate the manner of constructing the same;

30 Fig. 2 is a view in perspective showing the manner of securing one of the fastening devices to the legging; and Fig. 3 is a view showing the legging positioned upon the leg.

35 Similar reference characters refer to like parts throughout the several views of the drawing.

Referring now to the drawing, my invention is shown applied to a puttee legging indicated at 1, which in the present instance is constituted by a plurality of suitably shaped strips of cloth sewed together to provide a contour corresponding approximately to the shape of the leg. In the present instance I

40 employ four strips, and provide a seam in the rear portion of the legging, as at 2, and a seam at each of the side portions thereof, as at 3, the free edges coming at the front portion of the legging and preferably lapping

45 one upon the other.

By constructing the legging in the manner described, I am enabled to effect a large saving of material inasmuch as the four strips may be cut from a square piece of cloth without any waste.

60

In order that the legging may retain its shape when positioned upon the leg, I provide a plurality of stiffening members 4 which extend longitudinally of the legging. In this embodiment of my invention four 65 of these strips are employed, which are constructed of steel and are secured to the inner surface of the legging, said strips being held in position and concealed beneath strips 5 of cloth sewed to the legging, the seams coming 70 upon each side of the stiffening members, as clearly shown in Fig. 1 of the drawing. It will be noted that one of these stiffening members is provided near each free edge of the legging, and that one is provided intermediate the edges of each of the strips of material which form the rear portion of the legging.

75

In order to fasten the legging securely upon the leg, a strap 6 is secured to one of the 80 free edges of the legging at the lower extremity, said strap being adapted to be passed through a loop 7 formed upon the opposite free edge adjacent the point of fastening of the strap. The strap thereafter passes diagonally about the leg exteriorly of the legging, and at the front portion thereof intermediate the extremities of the legging said strap passes through loops 8 and 9 respectively provided upon each of the free edges of the 85 legging. The engagement of strap 6 with these latter loops prevents any relative longitudinal movement of the free edges of the legging. The strap thereafter again passes about the leg, and at the upper extremity of 90 the legging passes through a loop 10, whence it extends across the meeting edges of the legging and engages with a buckle 11. The several loops above described are formed by leaving slack portions in strips of cloth which are sewed to the material of the legging near the free edges thereof, said strips forming additional reinforcing means for the free edges of the legging.

95

In order to conveniently and securely fasten buckle 11 to the legging, the same is carried in a loop 12, one end of which lies upon the outer surface of the legging, the other end extending through an opening 13 cut therein, said ends being stapled, as at 14, or other-

100

105

110

wise secured together by means extending through the same and through the material of the legging.

The manner of fastening the legging about the leg, which should be obvious, is substantially as follows: The fastening strap being detached from the buckle and loosened, the foot may be inserted through the lower portion of the legging and the strap tightened and then inserted through loop 10 and engaged with the buckle.

It will accordingly be seen that I have provided a construction which is especially well adapted to attain the objects of my invention. The stiffening members insure the holding of the legging in a predetermined form and prevent the same from wrinkling or crinkling upon the leg. I am thus enabled to provide a legging which, while capable of being manufactured at a greatly reduced cost, has all the advantages of leggings of this type constructed of leather. Moreover, the legging is securely fastened upon the leg with a single pair of coacting fastening devices. The legging not only presents a sightly appearance, but may be adjusted upon the leg or removed with the expenditure of a minimum amount of time.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

Having described my invention, what I claim as new and desire to secure by Letters Patent is:

1. A legging adapted to be wrapped about the leg having a fastening member secured to one of the free meeting edges near one of the extremities thereof, said member being adapted to be passed about the exterior of

the legging and detachably secured to the other free edge of the legging near the opposite extremity thereof, and guides located upon the meeting edges intermediate the extremities of said legging through which said fastening member is adapted to extend.

2. A legging comprising a strip of flexible material adapted to be wrapped about the leg, a strap secured to the lower portion of one of the free edges thereof, a loop located upon the opposite free edge of the legging adjacent the point of fastening of said strap, said strap being adapted to be passed through said loop and then passed obliquely about the leg in an upward direction, a loop located upon the upper portion of the first mentioned free edge of the legging through which said strap is adapted to extend, a buckle upon the opposite free edge adjacent said last mentioned loop to which said strap may be adjustably secured, and a loop located upon each of the free edges of the legging intermediate the ends thereof through which said strap is adapted to extend.

3. A legging comprising a strip of material adapted to be passed about the leg and having free meeting edges, a plurality of relatively stiff members secured to the inner surface of said legging and extending longitudinally thereof, a strap secured to one of the lower free edges of said legging, a loop located upon the opposite free edge thereof adjacent the point of fastening of said strap through which the same is adapted to extend, said strap being adapted to be passed obliquely about the leg, a loop upon the upper portion of the first mentioned free edge of said legging through which said strap is adapted to extend, a buckle upon the opposite free edge of the legging adjacent said last mentioned loop to which said strap may be adjustably secured, and a loop arranged upon each of the free edges of said legging intermediate the ends thereof through which said strap is adapted to extend.

In testimony whereof I affix my signature, in the presence of two witnesses.

MORRIS ROSENWASSER.
